PIZZA TRAY

Daniel J. Meaney, Jr., Duluth, Minn., assignor to
Jeno's, Inc., Duluth, Minn.

Filed Jan. 21, 1971, Ser. No. 108,696

Term of patent 3½ years

Int. Cl. D7—02

U.S. Cl. D44—1

FIG. 1.

FIG. 2.

FIG. 3.

FIG. 1 is a top perspective view of a pizza tray showing my new design;

FIG. 2 is a side elevational view thereof; and

FIG. 3 is a top plan view thereof.

The bottom of the pizza tray is substantially plain and unornamented.

I claim:

The ornamental design for a pizza tray, as shown and described.
